(57) **ABSTRACT**

A new *Salvia* plant designated 'DH003' particularly distinguished by an evergreen shrub with a height of 100 cm and 4 to 6 glomerules per inflorescence, is disclosed.

1 Drawing Sheet

1

CROSS REFERENCE TO RELATED MATTER

The present application claims priority to U.S. Application No. 63/627,192, as filed on Jan. 31, 2024, the entire contents of which is incorporated herein by reference for all purposes.

Genus and species: *Salvia hybrida*.
Variety denomination: 'DH003'.

BACKGROUND OF THE NEW PLANT

The present invention comprises a new and distinct variety of *Salvia*, botanically known as *Salvia hybrida*, and hereinafter referred to by the variety name 'DH003'. 'DH003' originated from a cross of the proprietary female *Salvia* plant '1402-3-T1' (unpatented) and the proprietary male *Salvia* plant '1608-5-T1' (unpatented) in June 2019 in Boise, Idaho.

In fall of 2019 seeds were planted and a plant named 'DH003' was identified in the summer of 2020. 'DH003' was first vegetatively propagated by vegetative cuttings in Boise, Idaho. 'DH003' was found to reproduce true to type in successive generations of asexual propagation in Boise, Idaho via vegetative cuttings.

SUMMARY

The following are the most outstanding and distinguishing characteristics of 'DH003' when grown under normal horticultural practices in Boise, Idaho.

1. 4 to 6 glomerules per inflorescence;
2. Evergreen shrub; and
3. Shrub height of 100 cm.

DESCRIPTION OF THE PHOTOGRAPHS

These new *Salvia* plants are illustrated by the accompanying photographs of plants grown in a greenhouse in Boise,

2

Idaho. The colors shown are as true as can be reasonably obtained by conventional photographic procedures.

FIG. 1 is a whole plant photo of 'DH003' showing foliage, buds, and flowers. The photo is of a 2-year-old plant taken in March 2021 in Boise, Idaho.

FIG. 2 is close-up photo of 'DH003' showing foliage, buds, and flowers. The photo is of a 3-year-old plant taken in June 2022 in Boise, Idaho.

10 DESCRIPTION OF 'DH003'

The following detailed descriptions set forth the distinctive characteristics of 'DH003'. The data which define these characteristics were collected from asexual reproductions carried out in Boise, Idaho. Data was collected in January 2024 on 1 year old cuttings in 3 gallon containers grown in a plastic greenhouse. Color references are to The R.H.S. Colour Chart of The Royal Horticultural Society of London (R.H.S.), 4th edition (2001).

15 **20 Classification:**

Family.—Lamiaceae.

Genus.—*Salvia*.

Species.—*Hybrida*.

Common name.—Sage.

25 **Parents:**

Female parent.—*Salvia* plant '1402-3-T1' (unpatented).

Male.—*Salvia* plant '1608-5-T1' (unpatented).

30 **Plant:**

Propagation method.—Cutting.

Rooting system.—Fibrous.

Time to develop roots.—2 to 3 weeks.

Crop time.—8 weeks for 1 gallon container, 12 to 14 weeks for a 3 to 5 gallon container.

Suggested container size.—One gallon or 3 to 5 gallon.

<i>Use</i> .—Home gardens, commercial landscapes, native gardens, waterwise gardens.	Peduncle:
<i>Type</i> .—Perennial.	<i>Length (from uppermost leaf pair to base of lowest whorl of flowers)</i> .—approximately 8.7 cm to 9.2 cm.
Overall dimensions.—100 cm tall x 130 cm wide.	<i>Shape</i> .—Square in cross section.
<i>Cultural requirements</i> .—In ground, full to partial sun, infrequent deep watering, light shearing after main bloom season will keep the shrub compact.	<i>Width</i> .—0.25 cm.
<i>In containers</i> .—Full sun, well drained media, consistently moist, pinched in plug stage, pinched at least once more for a one gallon, at least twice more for a 3 or 5 gallon.	<i>Texture</i> .—Slightly tomentose.
<i>Hardiness</i> .—Zone 8a.	<i>Color</i> .—Base color of RHS 145B with overtones of RHS N79B.
<i>Form</i> .—Compact, rounded shrub.	Inflorescence:
<i>Growth habit</i> .—Compact.	<i>Type</i> .—Panicle verticillaster, typically 4 glomerules per stem.
<i>Blooming season</i> .—Spring through midsummer.	<i>Flower arrangement</i> .—Opposite cyme.
<i>Lastingness of blooms</i> .—Each flower lasts 2 days, each inflorescence lasts 4-6 weeks.	<i>Length</i> .—22 cm to 26 cm.
Stems (below first pinch):	<i>Width</i> .—5 cm to 7 cm.
<i>Condition</i> .—Semi-ripe wood.	<i>Number of florets per node</i> .—Approximately 8 to 28.
<i>Bark</i> .—Greyed Brown 199B.	Bracts:
<i>Shape</i> .—Square in cross section.	<i>Size</i> .—Lower bracts: Length: 0.9 cm. Width: 0.7 cm.
<i>Length</i> .—11.0 cm.	Upper bracts: Length: 0.6 cm. Width: 0.3 cm.
<i>Diameter</i> .—0.3 cm.	<i>Shape</i> .—Ovate to elliptic.
<i>Stem color (where exposed beneath bark)</i> .—RHS 193A.	<i>Color</i> .—RHS N79A at the apex fading to RHS 142C toward the base.
<i>Shape</i> .—Square becoming round with age.	Calyx:
<i>Texture</i> .—Smooth slightly tomentose becoming rougher with age.	<i>Shape</i> .—Tube.
Branches:	<i>Length</i> .—1.0 cm.
<i>Quantity</i> .—Too many to count.	<i>Width at base</i> .—0.1 cm.
<i>Shape</i> .—Square in cross section.	<i>Width across sepal apices</i> .—0.4 cm.
<i>Length</i> .—11 cm to 20 cm.	Sepals: Fused into calyx tube with 3 lobes, 1 adaxial, 2 abaxial.
<i>Width</i> .—0.3 cm.	<i>Length</i> .—0.03 cm (abaxial) and 0.05 cm (adaxial) from where tube flares into lobes to the apex.
<i>Internode length</i> .—0.8 cm to 1.9 cm.	<i>Width</i> .—0.01 cm (abaxial) and 0.03 cm (adaxial).
<i>Color</i> .—RHS 193A.	<i>Shape</i> .—Fused into tube, calyx lobes tapering to an acute apex.
<i>Anthocyanin</i> .—Absent.	<i>Apex</i> .—Acute.
Leaves:	<i>Base</i> .—Fused to calyx tube.
<i>Type, arrangement</i> .—Opposite.	<i>Margin</i> .—Entire.
<i>Attachment</i> .—Petiolate.	<i>Texture</i> .—Interior: Smooth. Exterior: Slightly tomentose.
<i>Quantity per branch</i> .—At least 18.	<i>Color (both surfaces)</i> .—RHS N79A at the apex fading to RHS 142C toward the base.
<i>Shape</i> .—Ovate to elliptic.	Flowers:
<i>Length (mature)</i> .—2.9 cm to 4.4 cm.	<i>Quantity</i> .—30 (or more) per glomerule.
<i>Width (mature)</i> .—1.6 cm to 2.1 cm.	<i>Aspect</i> .—45 degrees in relation to peduncle.
<i>Margin</i> .—Crenate.	<i>Shape</i> .—Tubular, opening to a bi-radially symmetric flower.
<i>Thickness</i> .—0.5 cm.	<i>Blooming period</i> .—Early to late summer.
<i>Surface (adaxial)</i> .—Rugose, slightly glandular pubescent.	<i>Persistence</i> .—Individual flowers last two days, individual inflorescences last 4-6 weeks.
<i>Surface (abaxial)</i> .—Net-veined, glandular pubescent.	<i>Fragrance</i> .—None.
<i>Color (adaxial surface)</i> .—RHS 189A.	Bud:
<i>Color (abaxial surface)</i> .—RHS 191B.	<i>Shape</i> .—Tube shaped with a rounded end.
<i>Venation</i> .—Pinnate in pattern, recessed from upper surface, protruding from lower surface.	<i>Dimensions (immediately before petal emergence)</i> .—Length: 0.9 cm to 1.0 cm. Diameter: 0.3 cm.
<i>Vein color</i> .—RHS 191D.	<i>Color</i> .—RHS 90C.
<i>Apex</i> .—Rounded.	<i>Surface</i> .—Smooth.
<i>Base</i> .—Rounded to cuneate.	Corolla:
<i>Fragrance</i> .—Musk, camphor, cineole.	<i>Shape</i> .—Tubular, opening to a bi-radially symmetric flower with 5 petals.
<i>Stipules</i> .—Absent.	<i>Length</i> .—1.9 cm to 2.1 cm.
Petiole:	<i>Width</i> .—Widest point of tube 0.4 cm; upper petal is 1.3 cm; lower petal is 1.5 cm.
<i>Shape</i> .—“D” shaped in cross section.	<i>Texture (both surfaces)</i> .—Smooth.
<i>Length</i> .—0.6 cm to 1.2 cm.	<i>Color (both surfaces)</i> .—RHS 92C fading to RHS 84D at the base of the tube.
<i>Width</i> .—0.15 cm.	
<i>Texture</i> .—Slightly tomentose.	
<i>Color</i> .—RHS 191D.	

Petals:

Quantity.—5.

Arrangement.—Tubular, opening to a bi-radially symmetric flower with 5 lobes.

Upper petal.—Shape: Elliptic. Length: 0.06 cm. Width: 0.3 cm. Texture: Adaxial surface: Smooth. Abaxial surface: Smooth. Apex: Rounded. Base: Fused to corolla tube. Margin: Entire. Color (both surfaces): RHS 92C.

Lower petal, lip.—Shape: Two lobed, elongated with elliptic lobes. Length: 0.5 cm, each lobe 0.2 cm long. Width: 0.03 cm to 0.04 cm. Texture (both surfaces): Smooth. Apex: Rounded. Base: Fused to corolla tube. Color (both surfaces): RHS 92C.

Lower petal, lateral lobes.—Shape: Elliptic. Length (each lateral lobe): 0.03 cm. Width: 0.02 cm. Texture: Adaxial surface: Smooth. Abaxial surface: Smooth. Apex: Rounded. Base: Fused to corolla tube. Margin: Entire. Color (both surfaces): RHS 92C.

Reproductive organs:

Stamens.—Quantity: 2. Filaments: Length: 0.07 cm from anther to attachment with corolla tube. Color: RHS N88C on the upper part, RHS N92D on the lower part.

Anthers.—Attachment, shape: Basifixed. Length: 0.2 cm. Width: 0.05 cm. Color: RHS 93A.

Pollen.—Amount: Medium. Color: RHS 2B.

Pistil.—Quantity: 1. Style: Length: 2.5 cm. Diameter: 0.3 cm. Color: RHS 91B fading to RHS 91C at base.

Stigma.—Shape: Forked. Length: 0.5 cm to 1.0 cm. Diameter: 0.01 cm to 0.02 cm. Color: RHS 90A.

Ovary.—Shape: Cylindrical. Length: 0.1 cm. Diameter: 0.1 cm. Color: RHS 145C.

Seeds:

Quantity.—2.

Shape.—Flattened oval.

Length.—0.3 cm.

Diameter.—0.15 cm.

Surface.—Smooth, shiny.

Color.—RHS N199C with darker vein-like markings of RHS N199B.

Disease and pest susceptibility: Occasional Powdery Mildew. Occasional Pithium or other water mold suscepti-

bility in water-logged or poorly drained soil. Occasional aphid infestation in early spring on new growth.

COMPARISON OF 'DH003' WITH PARENTAL LINES AND KNOWN VARIETY

'DH003' is distinguished from the female parent as described in Table 1 and the male parent as described in Table 2.

TABLE 1

Comparison with Female Parental Line		
Trait	Variety 'DH003'	Female parent '1402-3-T1'
Foliage retention	Evergreen	deciduous

TABLE 2

Comparison with Male Parental Line		
Trait	Variety 'DH003'	Male Parent '1608-5-T1'
Glomerules per inflorescence	4 to 6	1 to 2

'DH003' can be compared to the commercial *Salvia* variety 'Allen Chickering' (unpatented). Differences between the varieties are described in Table 3.

TABLE 3

Comparison with Similar Variety		
Trait	Variety 'DH003'	Commercial line 'Allen Chickering'
Height	100 cm	130 cm to 160 cm

I claim:

1. A new and distinct variety of *Salvia* plant named 'DH003' as shown and described herein.
